UNITED STATES PATENT OFFICE

134,563

DESIGN FOR A POSTURE CHAIR

Nathaniel T. Shepherd, Salt Lake City, Utah

Application April 16, 1942, Serial No. 106,585

Term of patent 14 years

To all whom it may concern:

Be it known that I, Nathaniel T. Shepherd, a citizen of the United States, residing at Salt Lake City, in the county of Salt Lake and State of Utah, have invented a new, original, and ornamental Design for a Posture Chair, of which the following is a specification, reference being had to the accompanying drawing, forming a part thereof,

Figure 1 is a front elevational view of a posture chair, showing my new design;

Fig. 2 is a side elevational view;

Fig. 3 is a rear elevational view; and

Fig. 4 is a top plan view thereof.

I claim:

The ornamental design for a posture chair, substantially as shown.

NATHANIEL T. SHEPHERD,
